UNITED STATES PATENT OFFICE.

SIDNEY WARWICK JENNINGS, OF MONTREAL, QUEBEC, CANADA.

COMBINED STEERING AND PROPELLING DEVICE.

No. 833,218.

Specification of Letters Patent.

Patented Oct. 16, 1906.

Application filed October 18, 1905. Serial No. 283,204.

To all whom it may concern:

Be it known that I, SIDNEY WARWICK JENNINGS, of the city of Montreal, Province of Quebec, Dominion of Canada, have invented certain new and useful Improvements in a Combined Steering and Propelling Device, of which the following is a full, clear, and exact description.

My invention relates to steering and propelling apparatus for vessels; and its object is to do away with the use of a rudder and utilize the propellers to steer the vessel. This object is accomplished by employing two oppositely-revolving and oppositely-pitched propellers so mounted that the angle between the axis of the vessel and the plane of the propeller's revolution may be changed at will by means of a steering mechanism, thus causing the thrust of the propellers to change the direction of the boat while forcing it ahead.

The advantage of this device is that the propelling force will be exerted to change the direction of a vessel instead of driving it in a straight line, as has heretofore been the case.

A further advantage is that in small motor-boats of the torpedo-stern type the motor will not have to be tilted back to allow the shaft to emerge from the hull in the proper place.

A still further advantage will be obtained in raising the water-line of the vessel, thus diminishing the necessity of a water-tight packing to prevent leaking.

In the drawings which illustrate my invention, and in which similar letters of reference refer to similar parts throughout, Figure 1 is a vertical longitudinal sectional view through the stern of a motor-boat, showing the application of my device thereto. Fig. 2 is an elevation of the steering-wheel located, preferably, toward the bow of the boat. Fig. 3 is a diagram of the steering-gear connections. Fig. 4 is a view of the under part of the stern of a boat with my device attached thereto, showing the bracket for supporting the same.

Referring to the parts, A designates the hull of a boat, B the deck, and C the coaming.

D is the main shaft from the engine or motor running in the bearing D' and provided on its aftermost extremity with a fixed bevel-gear D², adapted to mesh with the gear E' on the upper end of the hollow shaft E. The lower extremity of the shaft E is provided with a second bevel-gear E², which meshes with the gears G², rigidly attached to the

propellers G and G'. Each of these propellers is mounted on a shaft F², rigidly attached to the vertical spindle F, which passes through the hollow shaft E, and is provided toward its upper end with a suitable sprocket-gear H and at its upper extremity with a wheel K, which may be used to steer the boat if the steering-gear should become disabled. The lower end of the spindle F bears in the bracket O, which is strengthened by the transverse stays O'. Immediately below the sprocket-gear H is a ball-bearing F' to give strength and perfect mesh to the gears D² and E'. The hollow shaft E is led through a ball-bearing E³, which for security against leaking is provided with a sleeve E⁴, extending to the exterior of the hull, as shown in Fig. 1. A sprocket-chain J passes around the gear-wheel H and is led through guide-pulleys P to the front of the boat, where it passes around a sprocket L, rigidly attached to the steering-wheel M, which bears the manually-operated ratchet M', adapted to engage the ratchet-wheel N, rigidly attached to the bracket N'.

The operation of my device is as follows: The engine having been started, rotary motion is transmitted through the shaft D, which by means of the bevel-gears D² and E' rotates the hollow shaft E, provided at its lower extremity with the bevel-gear E², which meshes with the gears G² on the propellers G and G', turning them in opposite directions. Since these propellers are oppositely pitched and rotate in opposite directions, it will be seen that they both exert a thrust in the same direction. When it is desired to turn the boat, the ratchet M' is released from the ratchet-wheel N, and the steering-wheel M is turned as desired. This wheel carries with it the endless rope or chain J and transmits motion to the spindle F, which is provided with a fixed transverse arm F², on which the propellers revolve. When the spindle F is turned, the plane of the propellers is changed from its normal position at right angles to the line of direction of the boat, causing the propellers to exert a thrust in a sidewise direction. This side thrust swings the stern of the boat and causes it to turn as though it were momentarily pivoted on the bow. It will thus be seen that a vessel may be operated and controlled by means of the steering-gear alone without having to stop or reverse the engine. The propellers may be turned through any de-

sired angle and the boat driven straight ahead, turned in either direction, or driven backward by a single operator.

While I have shown the preferred form of my invention, I do not wish to limit myself to the precise construction shown, as I may use only one propeller instead of two and may make such other changes as fall within the scope of my invention.

10 Having thus described my invention so that the same may be readily understood by those skilled in the art to which it appertains, what I claim as new, and desire to secure by Letters Patent, is—

15 In a steering and propelling device for vessels, the combination of a horizontal main shaft, a hollow vertical driving-shaft engaging said main shaft, a bevel-gear on the lower end of said hollow shaft, a pair of op-

20 positively-pitched propellers adapted to be rotated in opposite directions by said hollow

shaft, a solid steering-shaft extending through said hollow shaft, a pair of transverse arms on said solid shaft for supporting the propellers, a brace supporting the lower end of 25 said solid shaft, a ball-bearing supporting the upper end of said hollow shaft, a sleeve surrounding said hollow shaft and extending from the exterior of the hull to said bearing, a sprocket-wheel on said solid shaft, a chain 30 engaging said wheel and connected to a steering-wheel in the forward end of the boat, and an independently-operated steering-wheel attached to the upper extremity of said solid shaft.

35

In witness whereof I have hereunto set my hand in the presence of two witnesses.

SIDNEY WARWICK JENNINGS.
